[57] CLAIM

The ornamental design for a magnifying device, as shown and described.

DESCRIPTION

FIG. 1 is a perspective view of a magnifying device showing my new design;

FIG. 2 is a side elevational view thereof;

FIG. 3 is a front elevational view thereof;

FIG. 4 is a top plan view thereof;

FIG. 5 is a rear elevational view thereof;

FIG. 6 is a bottom plan view thereof;

FIG. 7 is an opposite side elevational view thereof; and,

FIG. 8 is a perspective view of a second embodiment of the design shown in FIG. 1.
